UNITED STATES PATENT OFFICE.

WILLIAM F. STIFEL, EDWARD W. STIFEL, AND HENRY G. STIFEL, OF WHEELING, WEST VIRGINIA.

DESIGN FOR A FABRIC.

SPECIFICATION forming part of Design No. 35,125, dated September 17, 1901.

Application filed June 20, 1901. Serial No. 65,360. Term of patent 7 years.

To all whom it may concern:

Be it known that we, WILLIAM F. STIFEL, EDWARD W. STIFEL, and HENRY G. STIFEL, citizens of the United States, residing at 5 Wheeling, in the county of Ohio and State of West Virginia, have invented and produced a new and original Design for a Fabric, of which the following is a specification.

This invention relates to a new and original 10 design for a fabric; and the essential feature of the design resides in the fabric as illustrated in the accompanying facsimile-drawing, which shows a plan view of a portion of fabric embodying the design.

15 The design consists of a body 1, having stripes 2 thereon or displayed thereby, composed in each instance of a series of hearts which will be distinguishable from the ground of the body. The hearts in each

stripe are regularly arranged to have the alternate pairs thereof with the points directed toward each other. This disposition of the hearts is carried out throughout all the stripes of the fabric.

Having thus described the invention, what 25 is claimed as new is—

The design for a fabric, herein shown and described.

In testimony that we claim the foregoing as our own we have hereto affixed our signatures 30 in the presence of two witnesses.

WILLIAM F. STIFEL.
EDWARD W. STIFEL.
HENRY G. STIFEL.
